UNITED STATES PATENT OFFICE.

WILLIAM R. JEAVONS, OF CLEVELAND, OHIO.

WICK-TUBE.

No. 848,830.

Specification of Letters Patent.

Patented April 2, 1907.

Application filed November 3, 1906. Serial No. 341,860.

To all whom it may concern.

Be it known that I, WILLIAM R. JEAVONS, a citizen of the United States, residing at Cleveland, in the county of Cuyahoga and State of Ohio, have invented a certain new and useful Improvement in Wick-Tubes, of which the following is a full, clear, and exact description, reference being had to the accompanying drawings.

10 My invention relates to wick-tubes, and particularly to tubes such as are employed with oil-stoves. These tubes, as is well known in the art, comprise an inner and an outer tube suitably connected to form an annular chamber therebetween for the accommodation of the wick. The outer tube is provided with a housing for the reception of the spur-wheel by means of which the wick is raised and lowered.

20 In order to permit the wick to be raised and lowered with a minimum strain on the wick-raiser, the width of the space between the tubes is made somewhat greater than the thickness of the wick; but the upper ends of 25 the tubes converge slightly toward the wick to prevent the formation of a space between the wick when in raised position and the ends of the tubes, as such space would interfere with the satisfactory operation of the burner.

30 It frequently happens in the operation of these burners that some friction is developed between the wick and one or the other of the tubes, as by the swelling of the wick or by the rusting or roughening of the perforated 35 metal band or wick-carrier, which is placed on the outside of the wick and by means of which the same is raised and lowered by engagement with the spur-wheel of the wick-raiser. This binding of the wick in the 40 tubes, acting in some cases through a distance equal to the diameter of the wick-tubes on the spur-wheel, causes the wick to be tilted. As the tubes are generally made of light metal, the upper portions of the tubes at 45 points remote from the wick-raiser will yield, causing a tighter engagement of the wick by these portions of the tubes, with the result that it is often impossible to elevate the portion of the wick remote from the wick-raiser 50 above the tubes.

The object of my invention is to correct the defects noted and to insure an even elevation of the wick by the raiser. I accomplish this object by means of the construc-

tion shown in the drawings hereto annexed, 55 wherein—

Figure 1 represents a longitudinal sectional view through the central portion of a pair of wick-tubes constructed in accordance with my invention. Fig. 2 represents a transverse section taken on the line 2 2 of Fig. 1, the hollow boss or chamber for the spur-wheel, as well as said wheel, being omitted. Figs. 3 and 4 represent similar sectional details of modifications of the invention shown 65 in the preceding figures. Fig. 5 represents a detail of the outer tube shown in Figs. 1, 2, and 4.

1 represents an outer wick-tube, and 2 an inner wick-tube, said tubes being connected 70 at their lower portions, as by soldering. Between the tubes there is formed an annular space 3 for the reception of the wick 4.

5 denotes the supply connection for conducting oil to the lower end of this annular space, and 6 denotes the wick-raiser, the same being illustrated as a spur-wheel mounted on a shaft 7. This shaft may be inclined, as indicated in Figs. 1 and 5, whereby a rotary movement will be imparted to the wick as it 80 is raised and lowered.

The wick 4 may be provided with a wick-carrier 8, consisting of a sheet of perforated metal applied to the outside of the wick and extending from the bottom to a point somewhat below the top. The lower end of 85 8 is bent inwardly, and an upwardly-extending band 9 is soldered or otherwise suitably secured thereto to form therewith a U-shaped support for the lower end of the wick. The 90 annular space 3 is of greater width than is normally provided to permit the free movement of the wick-body between the inner and outer wick-tubes. To cause said tubes to closely engage the upper end of the wick, the 95 inner tube is flared outwardly and the outer tube inwardly to form a space therebetween, the width whereof is suitable to the thickness of the wick, as clearly illustrated in Fig. 1.

Notwithstanding the provision of the 100 somewhat enlarged space between tubes 1 and 2, it frequently happens, as hereinbefore explained, that the wick will bind against one or both of said tubes at a point remote from the wick-raiser. I have found that by 105 preventing the tilting of the wick in the section about the wick-raiser and at the place where the power is applied to the wick I am

enabled to prevent such friction as may be developed by the swelling of the wick or the roughening or rusting of the wick-carrier or otherwise from materially interfering with 5 the raising and lowering of the wick. I accomplish this result by narrowing the space adjacent the wick-raiser to substantially the thickness of the wick and carrier, whereby the tilting of the same by the operation of the 10 wick-raiser is prevented.

In Figs. 1 and 2 the narrowed space between the wick-tube is shown as provided by projecting outwardly and inwardly the portions of the inner and outer wick-tubes, respectively, which are adjacent the wick-raiser. The inner wall may be bent bodily outward at 10, the outwardly-bent section extending from near the bottom of the inner wick-tube to the top thereof and extending laterally on 15 both sides of the wick-raiser. This outward-bent section may occupy about one-quarter of the circumference of the inner wick-tube, more or less. I prefer to provide the outer wick-tube with several projections or corrugations 11. These corrugations extend from near the bottom of the outer wick-tube to or near the top thereof and are shown as somewhat inclined with respect to a vertical line to correspond to the direction of movement 20 or travel of the wick as it is raised or lowered by the operation of the spur-wheel, the shaft of which is indicated as inclined. In the case of a spur-wheel having a horizontal shaft the corrugations will extend vertically to 25 correspond to the direction of movement or travel of the adjacent portion of the wick. As in the case of the inner wick-tube, the portion of the outer wick-tube which is provided with the inward projections is about 30 one-quarter of the circumference of said tube.

In Fig. 3 I have shown a modification of the means for narrowing or contracting the space between the wick-tubes. In the embodiment shown in this figure the space may be narrowed by soldering or otherwise securing liners or strips 12 and 13 to the outer and inner surfaces of the inner and outer wick-tubes, respectively.

In the modification shown in Fig. 4 I employ an outer wick-tube similar to that shown in Figs. 1, 2, and 5 and with it an inner wick-tube having a series of similar corrugations 14 projecting into the annular space 3 and forming the desired narrow space with the 45 adjacent corrugated portion of the outer tube. As in the case of Figs. 1, 2, and 5, these corrugations are illustrated as extending at a slight angle with respect to a vertical line to correspond to the direction of movement or travel of the adjacent section of the wick where an inclined shaft is employed to 50 raise and lower the same.

In all of the modifications herein disclosed there is provided a narrowed section of the 55 annular space between the wick-tubes, and

this narrowed section extends a greater or less distance circumferentially on each side of the spur-wheel or wick-raiser and also both above and below the same to a distance covered by the wick-carrier in its excursions. In 7c the views herein shown this section extends substantially from the top to the bottom of the wick-tubes.

It will be apparent that other modifications of my invention may be made without 75 avoiding the spirit thereof, and hence I do not propose to be limited to the precise constructions illustrated in the various figures of the drawings, except as such constructions may be specifically embodied in the claims 80 hereto annexed or may be rendered necessary by the state of the art.

I claim—

1. The combination of a pair of wick-tubes, a wick therein, and a wick-raiser, each 85 of said tubes having only at the section thereof which includes the point of engagement between the wick-raiser and the wick one or more projections which extend into the space between the tubes and narrow the same 90 on both sides of said point of engagement and above and below the same, substantially as specified.

2. A pair of wick-tubes arranged to form an annular wick-space therebetween, a wick-raiser projecting into the space between said tubes, one of said tubes having one or more projections extending into the space between the tubes on both sides of said wick-raiser and extending above and below the same, the 100 narrowed space thus provided constituting a portion only of the complete annular space between said tubes, substantially as specified.

3. The combination of a pair of wick-tubes 105 arranged to form an annular space between them of greater width than the wick and so shaped as to contract said space at their upper ends to substantially the width of the wick, a wick and a wick-carrier in said space, 110 means for raising and lowering the wick, means being provided in proximity to the wick-raising means for contracting the width of one section of the wick-space in a vertical direction both above and below the wick-raiser, substantially as specified.

4. The combination of a pair of cylindrical wick-tubes forming an annular wick-space between them, a wick-raiser carried by the outer tube, said tubes being fashioned to contract or narrow the wick-space, at one section only, in a vertical direction above and below the wick-raiser and said section extending circumferentially on both sides of said wick-raiser, substantially as specified. 125

5. The combination of a pair of wick-tubes having an annular space therebetween, a wick and wick-carrier in said annular space, a spur-wheel for raising and lowering said wick, and means for narrowing said wick- 130

space to substantially the width of the wick and carrier at the section of said annular space which includes said wheel, such narrowed portion extending substantially from the top to the bottom of the wick-space.

6. The combination of a pair of wick-tubes having an annular space therebetween, a wick-raiser, and a wick and a wick-carrier in said space, said space being of greater width than is normally provided for the free movement of said wick and carrier therein and said space at the section including the wick-raiser being contracted to substantially the width of the wick and the carrier and such contracted space extending above and below said carrier, substantially as specified.

7. The combination of a pair of wick-tubes having therebetween an annular space which is contracted at the upper ends of said tubes, a wick and wick-carrier in said space, and a spur-wheel, means being provided for narrowing the width of the space between said tubes in the section which includes the spur-wheel to a width substantially equal to the width of the wick and carrier, the narrowed section thus provided extending both above and below said spur-wheel.

8. The combination of a pair of wick-tubes arranged to form therebetween an annular space which is narrowed at the upper ends of the tubes to substantially the thickness of the wick, a wick in said space, a wick-raiser for said wick, and means providing a contracted section in said annular space, said section extending from near the bottom of the tubes to near the top thereof and including between its circumferential limits the wick-raiser, substantially as specified.

9. The combination of a pair of wick-tubes having therebetween an annular space for the reception of a wick, a wick and wick-carrier within said space, a spur-wheel carried by the

outer tube and arranged to engage the wick-carrier and raise and lower the same and the wick, and means providing a narrowed vertically-extending section of the annular space between said tubes, such narrowed section being of substantially the same width as the width of the wick and carrier and extending on both sides of the spur-wheel and substantially from the bottom to the top of the wick-tubes, substantially as specified.

10. The combination of a pair of wick-tubes having an annular space therebetween, a wick and wick-carrier in said space, the upper ends of said tubes converging to narrow the space therebetween at this point, a wick-raiser carried by the outer tube and engaging the wick and carrier, one of said tubes having one or more projections extending into the annular space and so arranged as to narrow the width thereof at one section only, such narrowed section extending vertically from the lower to the upper portion of said tubes and circumferentially on both sides of the wick-raiser.

11. The combination of a pair of wick-tubes having therebetween an annular space which is contracted at the upper end of said tubes, a wick and wick-carrier in said space, and a spur-wheel engaging said carrier and wick, one of said tubes having one or more projections extending into the annular space to form a contracted or narrowed section thereof, said narrowed section extending from the upper to the lower portion of said space and extending laterally on both sides of the spur-wheel.

In testimony whereof I hereunto affix my signature in the presence of two witnesses.

WILLIAM R. JEAVONS.
